UNITED STATES PATENT OFFICE.

WILLIAM E. SWIFT, OF WAVERLY, ILLINOIS.

DEVICE TO PREVENT HENS FROM SETTING.

1,274,104.

Specification of Letters Patent. Patented July 30, 1918.

Application filed January 17, 1917. Serial No. 142,847.

To all whom it may concern:

Be it known that I, WILLIAM EDWARD SWIFT, a citizen of the United States, residing at Waverly, in the county of Morgan 5 and State of Illinois, have invented certain new and useful Improvements in Devices to Prevent Hens from Setting; and I do hereby declare the following to be a full, clear, and exact description of the invention, such 10 as will enable others skilled in the art to which it appertains to make and use the same.

This invention relates to improvements in the device for preventing hens from setting. 15

The object of this invention is the provision of a device which is adapted to be slipped around the body of a hen and located behind the wings and so constructed 20 as to prevent the hen from sitting down but permits the hen to eat, drink or run around when the device is applied thereto.

A further object of this invention is the provision of a device of this character which 25 is adapted to be slipped around a hen and located beneath the wings and is provided with a prong which lies upon the breast of a hen thus preventing the hen from sitting down upon the eggs and in a short while 30 breaks the hen of the desire to set upon the eggs so that she will start laying again.

A still further object of this invention is the provision of a device of this character which obviates the necessity of cooping the 35 hen up to break her of setting upon eggs and in the course of short while breaks the hen of the habit of setting upon eggs so that she will go about laying again.

A still further object of this invention is 40 the provision of a device which is adapted to prevent a hen from setting which is simple, practical and comparatively inexpensive in construction and one that can be manufactured and sold at a low cost.

With these and other objects in view this 45 invention consists in the novel combination and arrangement of parts hereinafter more fully described and set forth in the claim hereto appended.

In the drawing:

Figure 1 is a side elevation of the hen with my device applied as made in accordance with this invention,

Fig. 2 is a front elevation of my im- 50 proved device as made in accordance with this invention, and

Fig. 3 is a side elevation illustrating the adjusting means.

Like numerals of reference designate corresponding parts in all the figures of the 60 drawing.

Referring more particularly to the drawing the numeral 1 designates the lower member of my device and it is constructed of flat resilient metal which is bent back upon 65 itself centrally of its ends as at 2 to provide the spaced parallel arms 3 and 4 which arms are resilient and have their upper ends curved outwardly and upwardly as at 5 and the extreme upper ends of the curved arms 70 5 are reduced to provide lugs 6 and 7 which are bent back upon themselves as clearly shown in Fig. 2 of the drawing.

The lower member 1 is to be constructed of any suitable material such as metal, wire 75 or the like and the parallel arms 3 and 4 constitute a stop which will prevent the hen from sitting down when applied thereto. By virtue of the loop 2, the arms 3 and 4 may be adjusted or sprung out away 80 from one another so as to permit of the enlarging of the upwardly and outwardly curved portions 5 to permit of the device being adjusted to fit hens of various sizes without binding. It will also be noted that 85 the top member 8 may be readily sprung out to conform to the configuration of the lower member.

The top member is designated by the 90 numeral 8 and is constructed of flat metal or any other material suitable for the purpose and is substantially semi-circular and is provided adjacent each end with elongated slots which are adapted to receive 95 the lugs 6 and 7 therein so as to removably secure the top member to the lower member.

The upper member 8 is provided adjacent to one of its end slots with a plurality of slots 9 which are disposed above one end slots so as to increase or decrease the diameter 100 between the members 1 and 8 when assembled.

By connecting one of the lugs of the arms 5 in the slot 9 of the member 8 it can be readily seen that this constitutes the hinge 105 and the opposite member carrying the openings 9 may be hooked over the other lug and adjusted about the hen to which it is applied.

When applying the device:

The top member 8 is disconnected from the lower member 1 the top member is

straddled across the back of a hen and located under the wing 10 of the hen 11 the bottom member is then forced up about the breast of the hen the curved arms being located on opposite sides thereof, and the lugs disposed under the wings 10 and connected to the member 8 as previously described thus locating the parallel arms 3 and 4 in an inclined plane and projecting forwardly from the breast of the hen to which it is applied thereby preventing the hen from sitting down while the device is thereon.

What is claimed is:

15 A device to prevent hens from setting comprising an upper and lower member, the lower member being constructed of flat elastic metal looped at its medial portion to provide spaced diverging arms, the upper

terminals of said arms curved upwardly and outwardly to permit the device to be positioned and adjusted about the breast of a hen, the terminals of the arms bent outwardly and downwardly to provide attaching portions, the upper member being 25 formed of flat metal and being substantially semi-circular and provided adjacent each end with slots to receive the attaching portions of the lower member for detachably securing the members together, and said 30 arms extending downwardly so as to prevent the hen from setting.

In testimony whereof I affix my signature in presence of two witnesses.

WILLIAM E. SWIFT.
